WATERTIGHT BOX CONNECTER

Orville Kurtz Coleman, Mineola, N. Y., assignor to
The Rattan Manufacturing Company, New
Haven, Conn., a corporation of Connecticut

Application October 17, 1935, Serial No. 45,408

4 Claims. (Cl. 247—18)

This invention relates to improvements in water-tight connectors for electric-connection boxes.

One object of this invention is to provide an improved water-tight connector for electric-connection boxes which will effectively prevent the entrance of water past the cable and into the box.

Another object of this invention is to provide an improved water-tight connector formed of simple elements readily manufactured and readily assembled to produce a durable efficient construction at minimum cost.

With the above and other objects in view, this invention includes all improvements over the prior art which are disclosed in this application.

In the accompanying drawing, in which one way of carrying out the invention is shown for illustrative purposes:

Fig. 1 is a front elevation of a water-tight connector made in accordance with this invention, secured to a portion of an electric-connection box;

Fig. 2 is a right-side elevation of Fig. 1;

Fig. 3 is a rear elevation of Fig. 1;

Fig. 4 is a sectional view on line 4—4 of Fig. 1;

Fig. 5 is a sectional view on line 5—5 of Fig. 1;

Fig. 6 is a perspective view of the sealing-member; and

Fig. 7 is a perspective view of one of the anchor-members.

In the description and claims, the various parts are identified by specific names for convenience, but they are intended to be as generic in their application as the prior art will permit.

Referring to the drawing, 10 represents a plate or portion of an electric-connection box. The clamping-hood 11 is preferably hollow or concave and has a cable-hole 12 therethrough. Fitting in the clamping-hood 11 is a sealing-member 13 of readily-deformable material, preferably elastic material such as soft rubber or the like. The sealing-member 13 also has a cable-hole 14 therethrough.

Anchor-members 15 are located in the sealing-member 13 and extend through the cable-hole 15a in the plate 10, and have bent ends 16 adapted to engage against the inner face 17 of the plate 10 and have their opposite bent ends 18 provided with threaded openings 19 adapted to be threadedly engaged by the threaded shanks 20 of screws or bolts 21. The covered electric cable 22 extends through the cable-holes in the clamping-hood, sealing-member and plate 10.

By adjusting the screws 21 to the desired degree, the clamping-hood 11 crowds or compresses the sealing-member 13 tightly against the outer

face 23 of the plate 10 to render water-tight, the area of engagement of the sealing-member 13 with the plate 10 around the cable-hole 15a, and also crowds or compresses the sealing-member 13 into close water-tight engagement with the surface of the cable 22.

In applying the water-tight connector to the plate 10 of a box, the bent ends 16 of the anchor-members 15 can be readily sprung toward one another to have their extreme ends pass through the cable-hole 15a of the plate 10, owing to the elastic nature of the sealing-member 13 in which the anchor-members 15 are embedded. Then, after the ends 16 have been properly inserted through the opening 15a, the cable 22 can be passed through the cable-holes in the parts of the device, and the screws 21 can be operated to seal water-tight, the areas of engagement between the sealing-member 13 and the cable 22 and between the sealing-member 13 and the plate 10, to thus provide a water-tight construction that will prevent leakage of water into the electric-connection box on which it is used. The anchor-members 15 and screws 21 constitute adjustable clamping-means.

The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

I claim:

1. A water-tight connector for electric-connection boxes comprising: a hollow clamping-hood having an end-wall provided with a cable-hole therethrough; a sealing-member of readily deformable material and having a cable-hole therethrough; adjustable clamping means for attaching said clamping-hood to a plate of a box provided with a cable-hole through said plate and with said sealing-member against one face of said plate and between said clamping-hood and said plate and with said cable-holes of the clamping-hood, sealing-member and plate in general alignment, said adjustable clamping-means including bolts adapted to extend through said end-wall and into said sealing-member and anchor-members adapted to be located inside of said clamping-hood and adapted to connect said bolts with said plate, and said clamping-means being adapted to be adjusted to compress said sealing-member between the clamping-hood and

plate and cause said sealing-member to seal water-tight, the area between said sealing-member and plate surrounding the cable-hole through the plate and the area between said sealing-member and a cable extending through the cable-hole of the sealing-member.

2. A water-tight connector for electric-connection boxes comprising: a hollow clamping-hood having a cable-hole therethrough; a sealing-member of readily-deformable material and having a cable-hole therethrough; adjustable clamping-means for attaching said clamping-hood to a plate of a box provided with a cable-hole through said plate and with said sealing-member against one face of said plate and between said clamping-hood and said plate and with said cable-holes of the clamping-hood, sealing-member and plate in general alignment, said adjustable clamping-means including a pair of spaced-apart bolts adapted to extend into the interior of said clamping-hood and a pair of anchor-bars adapted to threadedly interconnect said bolts and said plate, and said clamping-means being adapted to be adjusted to compress said sealing-member between the clamping-hood and plate and cause said sealing-member to seal water-tight, the area between said sealing-member and plate surrounding the cable-hole through the plate and the area between said sealing-member and a cable extending through the cable-hole of the sealing-member.

3. A water-tight connector for electric-connection boxes comprising: a hollow clamping-hood having a cable-hole therethrough; a sealing-member of readily-deformable material and having a cable-hole therethrough and adapted to fit in said clamping-hood; adjustable clamping-means for attaching said clamping-hood to a plate of a box provided with a cable-hole through said plate and with said sealing-member against one face of said plate and between said clamp-

ing-hood and said plate and with said cable-holes of the clamping-hood, sealing-member and plate in general alignment, said adjustable clamping-means including threaded means and anchor-means adapted to threadedly engage said threaded means and adapted to be passed through the cable-hole in said plate and engage said plate, and said clamping-means being adapted to be adjusted to compress said sealing-member between the clamping-hood and plate and cause said sealing-member to seal water-tight, the area between said sealing-member and plate surrounding the cable-hole through the plate and the area between said sealing-member and a cable extending through the cable-hole of the sealing-member.

4. A water-tight connector for electric-connection boxes comprising: a clamping-hood having a cable-hole therethrough; a sealing-member of readily deformable material and having a cable-hole therethrough; adjustable clamping-means for attaching said clamping-hood to a plate of a box provided with a cable-hole through said plate and with said sealing-member against one face of said plate and between said clamping-hood and said plate and with said cable-holes of the clamping-hood, sealing-member and plate in general alignment, said adjustable clamping-means including anchor-means adapted to be passed through the cable-hole in said plate and engage against the other face of said plate, and said clamping-means being adapted to be adjusted to compress said sealing-member between the clamping-hood and plate and cause said sealing-member to seal water-tight, the area between said sealing-member and plate surrounding the cable-hole through the plate and the area between said sealing-member and a cable extending through the cable-hole of the sealing-member.
